UNITED STATES PATENT OFFICE.

HERMAN RINGEL, OF NEWARK, NEW JERSEY, ASSIGNOR TO CONVERTERS PAPER COMPANY, OF NEWARK, NEW JERSEY, A CORPORATION OF NEW JERSEY.

GARMENT BAG.

Application filed July 23, 1926. Serial No. 124,425.

This invention relates to improvements in garment bags as employed for the storage of clothing at unused periods.

Such bags are made of strong thick paper, of a size commensurate with their purpose, preferably open at one of their longitudinal edges, which, after the wearing apparel has been entered, is tightly folded or otherwise enseamed to prevent the entrance of moths and other insects destructive to the clothing, as well as dust, the bag being substantially air tight.

Usually the garments are disposed on a hanger attached interiorly of the bag to a supporting hook by which the filled bag is suspended on a pole or hook in a closet or like storage room.

As the articles so protected are usually stored for a considerable period of time, it is quite essential that they be disposed within the bag as smoothly as possible, free from folds, wrinkles, creases, etc., so that when required for use they will present a desirable neat appearance.

It is however quite difficult for one person to properly maneuver the garments and bag at the same time, as the tendency of the bag is to close and its size renders it an awkward object to handle when placing the articles therein, the result frequently being a messy, untidy appearance of the garments when removed as required for use.

It is therefore the principal object of the present invention to provide means, operable at will, whereby the side walls of the bag may be distended to such an extent that articles of clothing, neatly arranged upon a common hanger, can be entered and allowed to hang pendant within the bag without distortion, or even adjusted by a single operator without difficulty, the bag thereafter collapsing to its normal thickness, plus the goods enclosed in it.

A further feature is in the provision of a single hook-like support at the end of the bag having interior elements, operating in conjunction with spreader plates, whereby the bag may be distended uniformly from within or permitted to collapse as desired.

Another purpose is to produce a single unitary wire element having the combined functions of suspending hook, hump opener and hanger ring support.

Other advantages will hereafter appear in

the detailed description of structural elements, taken in connection with the accompanying drawing, forming a material part hereof, and in which:

Figure 1 is a side elevational view of an embodiment of the invention, partially broken away at one end.

Figure 2 is a fragmentary sectional view taken on line 2—2 of Figure 3 and drawn to an enlarged scale.

Figure 3 is a sectional view taken in a plane at a right angle to Figure 2, showing the walls of the bag, in a normal closed position.

Figure 4 is a view similar to Figure 3 but showing the bag walls as distended.

Figure 5 is a fragmentary side elevational view of a modified form of bag support and opening device.

Figure 6 is a longitudinal sectional view taken on the center line of Figure 5 showing the bag as expanded.

Figure 7 is a perspective view of the hook support plate in detail.

In common with ordinary garment bags the present embodiment is constructed from a single sheet of strong, dense paper of suitable thickness and size, folded at the bottom 5 to present side walls 6 and 7, permanently secured along one longitudinal edge by a cemented seam 8 and at the top by a similar seam 9, the opposite longitudinal edge being open to permit the entrance of articles and thereafter folded and seamed dust proof in any preferred manner.

Cemented to the inner surfaces of the side walls 6 and 7, at approximately the center of their width, is a stiff card-board bent to present leaf plates 10 and 11, integrally connected at the fold 12, the same being disposed at the top of the seam 9.

A small perforation at the center of the fold and seam permits passage of a wire 13, its outer portion being formed into an open hook 14 engageable with a pole or support and its inner portion bent and folded upon itself to produce a rightangle hump 15 disposed in the plane of the hook.

A continuation 16 of the wire is in register with the main upper portion 13 and terminates in a looped eye 17 carrying a ring, as shown in broken lines, in which may be engaged the hook of a garment holder as will be clearly understood.

The wire element 16 is enclosed by the bight 18 of a bent metal clip, the end portions 19 of which are passed through appropriate openings in the plate 10 and turned oppositely outward, tightly over its outer surface interjacent the bag wall 6, retaining the wire element thereagainst but permitting it to rotate, and the opposite end of the bag may be similarly supplied with 10 like members if desired.

The operation of opening or expanding the bag is accomplished by grasping the hook 14 and rotating its wire stem until the hook is disposed transversely to the bag, as 15 shown in Figure 4, in which position the hump 15 will force the plate 11 outward, away from the plate 10, obviously expanding the bag side walls and presenting a ring in the eye 17 in position to receive a hook 20 or like garment supporting device.

When the articles have been entered through the open side edge and adjusted within the bag the hook 14 is again actuated in the manner of a handle, turning the hump 25 to lie flat between the plates 10 and 11 which will thus assume the position shown in Figure 3.

In Figures 5 and 6 a conventional closet pole is designated by the numeral 20, engageable with which is a wire hook 21 having a 30 stem 22 extending downward along one of the outer sides of the bag and having at its end a closed loop 24.

A thin flat sheet metal plate 25, shown in 35 detail in Figure 7, and of any preferred contour, is formed with an opening 26, the metal being sheared to present a plurality of indent prongs 27 extending around the edge of the opening, these prongs being adapted 40 to pierce the bag material and reinforcement 10 to be clinched on the inner side firmly securing the plate to the bag.

Near the upper end of the plate are two 45 longitudinally spaced smaller openings 28 and adjacent the space therebetween are a pair of elongated slots 29, these slots aiding in stretching the metal between them and the openings 28 when forming a raised integral clip 30 in which the loop 24 engages.

It will be understood that the stem 22 of 50 the supporting hook may be partially rotated in the clip, which is drawn to the lower end of the loop in supporting the weight of the bag and its enclosures.

Fixed on the inner side of the bag, opposite the plate 25, is a second plate, a dupli-

cate in every particular, but disposed in a reverse position.

Another wire hook 31 is provided with a 60 stem 32 passing through the loop 30 of the inner plate and bent at a right angle 33 to form a hump 34, the other leg 35 of which extends nearly or quite to the stem 32, below the loop 30, preventing accidental displacement. 65

In order to expand the bag, an operator reaches in through the open side edge of the bag to grasp and turn the hook 31, which action obviously moves the hump 34 from the position shown in Figure 5 to that illustrated in Figure 6, pressing the bag sides apart. 70

When the garments have been suspended on the hook 31 it may be partially rotated into its initial, flat position, allowing the 75 bag to assume its normal flat condition.

Although the foregoing is descriptive of preferred embodiments of the invention, it will be apparent that minor changes may be made in its construction, without the exercise of invention or conflicting with the 80 scope of the claims hereto appended.

Having thus described my invention, what I claim as new and desire to secure by Letters Patent, is:—

1. A garment bag comprising a paper receptacle open at one of its longitudinal edges, integral stiff plates secured to the inner surfaces of the bag sides and folded midway their length, said plates being disposed 90 at the end of the bag, a hook having a stem entering the end folds of the bag and plates, a hump on said stem extending in the plane of said hook, means to confine said stem against one of said plates, and an eye at the 95 end of said stem extending into the bag.

2. In a garment bag having expansible sides, a stiff plate folded at its median line and secured to the inner surface of the bag side walls at the top thereof, a wire bent to 100 present a hook the stem of said hook extending into the bag through its end edge and between the elements of said plate, a hump on said stem to operably engage said plates, a clip securing said stem to one of said plates, 105 said stem being rotatable in the clip, and a looped eye at the inner end of said stem, said hump and eye being disposed in the plane of said hook.

This specification signed this 22nd day of 110 July, 1926.

HERMAN RINGEL.
